BUILDING MATERIAL

Donald H. Sweet, Evanston, Ill., assignor to The Logan-Long Company, Chicago, Ill., a corporation of Ohio

Application June 28, 1930. Serial No. 464,526

6 Claims. (Cl. 108—7)

My invention relates to building material, and includes among its objects and advantages the fabrication of improved roofs and an improved lock shingle for use in fabricating such roofs. In the accompanying drawing:

Fig. 1 is a diagram indicating how my shingle can be cut from a strip of material without waste.

Fig. 2 is a plan view of a portion of a two-thickness roof.

10 Fig. 3 is a plan view of a portion of a one-thickness roof.

The shingle according to the invention, in the embodiment selected for illustration, comprises a quadrilateral body 10 having an upper edge 12 and a lower edge 14. The side of the shingle is defined by edge portions as follows: a vertical edge portion 16 and an inwardly extending horizontal edge portion 18, together defining a locking tab 20. There follows an upwardly and outwardly inclined edge portion 22 and a horizontal outwardly extending edge portion 24 defining a re-entrant angle 26. An inwardly and upwardly inclined portion 28 and a horizontal outwardly extending edge portion define a second 20 re-entrant angle 32, vertically aligned above the first re-entrant angle 26. The portions 24 and 28 are joined by a curved portion 34.

Beyond the midpoint of the horizontal portion 30, the rest of the side of the shingle is a geometrical replica of the lower portion, reversed by rotating the same 180° about the midpoint of the horizontal portion 30. This develops an upwardly and inwardly inclined portion 36, joined by a concave curve to a horizontal outwardly extending portion 38, above which is the upwardly and outwardly extending straight portion 40, the inwardly extending horizontal portion 42, and the vertical portion 44 reaching the upper edge 12.

In laying a two-thickness roof according to the invention, the first course 46 may be started with the usual starting strip, and the second course 48 is laid with its tabs 20 hooked into the angles 26 of the course below. Similarly, the succeeding courses 50, 52, 54 and 56 are each laid with their tabs 20 hooked into the angles 26 of the course below. When laid in this way, the angles 32 perform no interlocking function, being merely part of the contour of the portion of the shingle underlying the courses higher up. It will be observed that the lower edge of shingles in course 56 is substantially coincident with the upper edge of the shingle in course 48, so that no portion of the roof is covered by less than two thicknesses of material.

55 Referring to Fig. 3, the first course 58 may be

started as in Fig. 2, but the next course 60 is laid with its tabs hooked into the angles 32 of the course below, and the succeeding courses 62, 64, and 66 are all similarly laid. This leaves the angle 26 of each shingle performing no 60 interlocking function. It also leaves the edge portions 24, 34, and 28 of each shingle exposed to define a slight offset or shelter in the otherwise approximately hexagonal contour of the exposed portion of the shingle. It will be noted that shingles 66 overlap shingles 62 by a distance indicated at 68, which may be made the minimum necessary to prevent rain beating through the roof at this point, so that as large a proportion as possible of the roof of Fig. 3 is 70 covered by one thickness of material only.

It will also be observed that the roof of Fig. 2 and the roof of Fig. 3 may both be laid by similar operations with identical material, and that the roof of Fig. 3 is equally regular in its finished 75 appearance with that of Fig. 2, so far as identity of all the exposed area is concerned.

Without further elaboration, the foregoing will so fully explain the gist of my invention that others may, by applying knowledge current at 80 the time of application, readily adapt the same for use under various conditions of service.

I claim:

1. A shingle having a generally quadrilateral body with the upper and lower edges parallel, and 85 upwardly divergent sides defined by a vertical edge joining a horizontal inwardly extending edge forming a locking tab at the lower corner of the shingle, then from the inner end of the horizontal edge a straight upwardly and outwardly extending edge joining below the middle of the shingle with a horizontal outwardly extending edge which is curved at the end and joins an upwardly and inwardly extending edge joining with a horizontal outwardly extending 90 edge at the mid-portion of the shingle, the contour of the upper portion of the sides being complementary in reverse to the lower portions.

2. A shingle having a generally quadrilateral body with the upper and lower edges parallel, and 100 sides defined by a vertical edge joining a horizontal inwardly extending edge forming a locking tab at the lower corner of the shingle, then continuing in a straight upwardly and outwardly extending edge joining with a horizontal outwardly 105 extending edge which is curved at the outer end and joins an upwardly and inwardly extending edge joining with an outwardly extending horizontal edge at the middle of the shingle, the upper portions of the sides being complementary 110

in reverse to the lower portions, the notch formed at the upper end of the upwardly and outwardly extending edge in the lower portion of the side being in vertical alignment with the notch 5 formed at the inner end of the horizontal edge at the middle of the shingle.

3. A roof composed of uniform shingles having the upper and lower edges parallel and having locking tabs on the lower corners and notches 10 in the sides, the tabs on one course being hooked into the notches in the preceding course, the notches being located so that the upper edge of one course coincides with the lower edge of the second higher course.

15 4. A shingle having a generally quadrilateral body with locking tabs at adjacent lower corners and a plurality of notches in the sides above said locking tabs, said notches including a lower notch spaced from the upper edge of the adjacent 20 locking tab by one-fourth the height of the shingle, the lower notches being adapted to receive the tabs of the shingles in the next course to provide a two-thickness roof, and an upper notch spaced from the top of the locking tab by a distance 25 equal to the height of the shingle minus the necessary overlap in a one-thickness roof divided by two, the upper notches being adapted to receive the tabs of the shingles in the next course when a one-thickness roof is being laid.

30 5. A shingle having a generally quadrilateral

body with locking tabs at adjacent lower corners and a plurality of notches in the sides above said locking tabs, said notches including a lower notch spaced from the upper edge of the adjacent locking tab by one-fourth the height of the shingle, the lower notches being adapted to receive the tabs of the shingles in the next course to provide a two-thickness roof, and an upper notch spaced from the top of the locking tab by a distance equal to the height of the shingle minus the necessary overlap in a one-thickness roof divided by two, the upper notches being adapted to receive the tabs of the shingles in the next course when a one-thickness roof is being laid, the vertical separation between said two notches being substantially the height of the locking tabs.

6. Shingles having locking tabs at adjacent lower corners of each shingle, and a plurality of notches in each side of each shingle above said locking tabs, said notches being adapted to receive the locking tabs of shingles in the next course, certain of said notches being positioned to interlock the shingles into a one thickness roof with one predetermined figure design, and certain other of said notches being positioned to interlock the shingles into a two thickness roof with a different design.
